UNITED STATES PATENT OFFICE

CHARLES F. MEILINK, OF TOLEDO, OHIO

FIREPROOF SAFE

Application filed October 8, 1923. Serial No. 667,222.

This invention relates to features of safe or vault fronts.

This invention has utility as a folded sheet metal door jamb and door frame construction.

Referring to the drawings:

Fig. 1 is a perspective view of an embodiment of the invention in a safe;

Fig. 2 is a fragmentary section on the line II—II, of Fig. 1;

Fig. 3 is a fragmentary section on the line III—III, of Fig. 1;

Fig. 4 is a perspective view looking into a corner of the door jamb, parts being broken away;

Fig. 5 is a fragmentary perspective view of a door corner as interfitting with a corner of the door jamb;

Fig. 6 is a fragmentary perspective view 20 of the central corner of the safe door as to be first closed, and

Fig. 7 is a fragmentary perspective view of the central or inner corner of the door to be last closed.

Angle iron metal rectangular frames 1, 2, have extending therebetween outer sheet metal housing 3 spaced by heat resisting filler or insulation 4 from inner housing 5. The housing front angle frame 2 has its inwardly extending leg or flange 6 directly coact with outer section 7 of the door jamb. This section 7 as nesting within the leg 6 of the frame 2, has an extension 8 snugly fitting within the outer housing wall 3 as mounted within this front frame 2. This jamb 7 has from its plane a straight portion 9 extending perpendicularly inward to undercut 10, extending down from one side for groove 11. From the groove 11 and parallel to the jamb portion 7 there is groove side portion 12 extending directly inward to portion 13, parallel with the portion 9. This portion 13 extends to portion 14 diverging from the portion 10, and terminates at portion 15 parallel with the portions 9, 11, 13. This portion 15 extends to portion 16 slightly diverging from the portion 14 to provide an undercut. This portion 16 terminates in inwardly extending flange 17 parallel with the portions 8, 9, 11, 13, 15. This flange 17 fits over the outer free

end of the inner wall 5. This hinge side of the jamb accordingly provides a groove 18 on one side of the plane of the axis of hinge pin 19, said plane being perpendicular to the plane of the jamb portion 7, and a second groove 20 on the opposite side of such plane. Furthermore, these grooves 18, 20, diverge from each other, and are oppositely undercut.

The door jamb as extending between the hinge sides thereof, which hinge sides herein are shown vertically extending, is also provided with stepped portions. This jamb frame is of folded sheet metal construction, and in practice may be welded up as a continuous endless unit with the portions 7, 8, continuous. At the portions of the jamb as connecting the hinge sides there extends rearwardly from the jamb portion 7, a straight portion 21 to inwardly extending portion 22, which terminates in a portion 23 parallel with the portion 21. This portion 23 terminates forwardly in a portion 24 parallel with the portion 7, and extends to rearwardly extending portion 25 parallel with the portion 21. This rearwardly extending portion 25 terminates in a portion 26 extending over to forwardly extending portion 27 parallel with the portion 25. This portion 27 terminates in a portion 28 parallel with the portions 7, 22, 24, 26, which terminates in a portion 29 parallel with the portions 8, 21, 23, 25, 27. There is accordingly provided directly forwardly open grooves 30, 31, in the non-hinge carrying side portions of the jamb.

At the corners of the door jamb the groove 18 is continuous in merging with the groove 30, while the groove 20 is continuous in merging into the groove 31. Ribs 32, 33, extend into the grooves 18, 20, adjacent said merging, while ribs 34, 35, 36, merge directly into the adjacent jamb structure bordering the other ribs and grooves. The ribs 32, 34, are discontinuous, and likewise the ribs 33, 35. This corner is a mutually reinforced stiff construction of light material maintaining door packing or sealing effectively and independently of any weakening of the construction.

The safe is shown as of the double door type having first door 37 and second door 38. In door operation, the door 37 is closed, handle 39 operated to throw its bolts, then the door 38 is closed, its handle 39 operated, and then by means of spindle 40, the final locking is completed.

The door 37 is shown as comprising an outer plate 41, an inner plate 42 with insulation filler 4 therebetween. The outer plate 41 is mounted by leaf hinges 43 engaging with hinge pins 19 carried by hinge leaves 44 upon the frame 2 and the door jamb.

These doors are provided with endless door frames. These frames on the hinge side comprise flange portion 45 adjacent the plate 41. Inwardly extending from this flange portion 45 and parallel to the jamb portion 9 is straight portion 46 extending to portion 47, parallel with the portion 10, and terminating in portion 48, parallel with the portion 11. This portion 48 extends to portion 49 extending toward the jamb portion 12 when the door is in closed position. This portion 49 terminates in portion 50 parallel with the portion 12 extending to portion 51 parallel with the portion 15. This frame from the portion 51 has portions 52, 53, 54, 55, respectively parallel with the portions 14, 15, 16, 17, of the jamb. This portion 55 terminates in portion 56 parallel with the portion 45 extending inward to provide offset seat 57 for the inner door plate 42.

The companion or second door 38 has outer plate 58, and inner plate 59 with intermediate insulation filler 4. At its hinge side the frame for this second door is similar to the frame of the first door, and these frames accordingly at their hinge sides provide diverging ribs 60, 61, on opposite sides of the plane of the hinge pivots 19 as perpendicular to the planes of the respective doors.

Extending from the hinge sides of the respective doors, the door frames comprise portions 62, 63, 64, 65, 66, 67, 68, 69, 70, respectively parallel with the door jamb portions 21, 22, 23, 24, 25, 26, 27, 28, 29. There is accordingly provided ribs 32, 33, as straight ribs for directly respectively extending into outwardly open grooves 71, 72, of the door frame as the offset or diverging ribs 60, 61, extend respectively into undercut grooves 18, 20. The grooves 71, 72, are bordered by ribs 73, 74, 75. Between the ribs 60, 61, is groove 76. These ribs 73, 74, are continuous and merge into the ribs 60, 61, which respective ribs 60, 61, adjacent such merging are reduced by grooves 71, 72, running out therethrough. This running out of the grooves 71, 72, is not of an extent to fully sever the respective ribs 60, 73, and 61, 74.

The first door 37 at its side remote from its hinge has the door frame 45 stepped toward the door frame portion 56 by portions 77, 78, 79, 80, 81, 82, 83, 84, 84', to provide

grooves 85, 86, and ribs 87, 88. The rib 88 extends to merge with rib 75 but owing to groove 72 running out, this rib 88 does not merge with the rib 74. The groove 71 runs out so that the rib 87 is short of merging into rib 73.

The second door 38 has at its edge remote from its hinge mounting and between its frame portions 45, 56, stepped portions 89, 90, 91, 92, 93, 94, 95, 96, 97, respectively in closed position parallel to the portions 77, 78, 79, 80, 81, 82, 83, 84, 84', of the frame portion of the first door 37.

This second door accordingly provides the ribs 98, 99, 100, spaced by grooves 101, 102. The ribs 98, 99, do not merge into the respective ribs 73, 74, for the reason that the grooves 71, 72, run out therebetween. The grooves 101, 102, extend into the respective grooves 71, 72.

The stepped structure of ribs and grooves, it is to be noted, is of differing character as on adjacent sides of the jamb and on adjacent sides of the door frames, but as merging into each other at the jamb, said interlocking stepped structure is continuous. The only running out occurs between the pair of doors and such running out cooperates in continuity as to the jamb.

The inset placing of the pivot axis for the hinges is such that the outer rib and groove in approximating a tangent on one side of such pivot axis plane diverges from the inner ribbed structure on the opposite side of such plane. Accordingly these diverging groove and rib interlocking joints are effective in cooperation for binding sealing instead of release when the safe is subjected to temperature strains as in case of being in a conflagration. As the heat expansion comes into play the bulging and swelling only serves more tightly to lock and bind the doors against opening. There is accordingly a fire proof maintained sealing under the most trying conditions of practice.

Effectiveness of this joint against transmitting heat is enhanced by compressible packing 103 in the jamb grooves between the groove side 10 toward the hinge and the rib side 47, said packing 103 normally being placed in the groove side 10. Similar packing 103 is placed in the groove side 14 to have the door rib side 52 crowd thereagainst as the heat acts in tending to bulge or expand the safe structure. As this packing 103 extends into the corners it overlaps or abuts packing 104 in groove root portions 22, 26, against which abut door frame ribs 30, 68. Accordingly this sealing by abutting the packing is endless or continuous with the groove and rib interlocking feature between the door frame and jamb. In the double door structure the joint between the doors is also sealed by packing 104 in the groove roots 78, 130

82, where it is there abutted by the rib portions 90, 94.

Bulging or expanding of the frame 2 in the structure as herein disclosed has its tendency to disturb the joint minimized due to the clearance between the web 6 of the frame 2 and the jamb section 9. While the hinge leaf 44 is mounted on the frame 2, the exposure of the jamb section 7 as to its thin wall between the portion 9 and the frame leg or web 6 creates a region of thin metal between the jamb proper and the frame. This means that in high heating emergency, expansion or bulging tendency of the frame 2 may react for stretching this section 7 of thin highly heated metal instead of tending to pull open the more rigid joint structure, the filling tending to reduce heat penetration and thereby render the joint sufficiently rigid to allow of this action. This is accordingly a factor in the production of this heat resistant joint. Still a further feature against heat conductivity is the pocket 105 as a chamber between the groove side 12 and the rib side 49. This chamber forms a dead air space of heat resistant value.

What is claimed and it is desired to secure by Letters Patent is:—

1. An angle metal frame, an outer wall nested in an endless rearwardly extending flange of said frame, an inner wall parallel to said outer wall, a filler therebetween, and a folded sheet metal door jamb nesting within the inwardly extending flange of said frame and extending to within said inner wall, said folded jamb extending directly outward in the direction of the inner wall to fit on the inner side of said wall, the outer side of the jamb as forming a door opening extending perpendicularly inward, and an intermediate portion of said jamb comprising a rib between a pair of grooves, said grooves being intermediate said directly outward and perpendicularly inward portions and in addition thereto.

2. A door jamb having a hinge side, along said side an undercut groove, and along its parallel sides extending from said hinge side outwardly open grooves merging directly into said undercut groove to form a continuous groove, and a door coacting with said jamb.

3. A door jamb having a hinge side, along said side a plurality of undercut grooves, and along its parallel sides extending from said hinge side outwardly open grooves, said undercut and outwardly open grooves approximating a common depth and merging directly to approximate parallel continuous grooves, and a door coacting with said jamb.

4. A door having a hinge side, along said side an offset rib, and along said door parallel sides extending from said hinge side an outwardly straight rib merging directly into said offset rib to form a continuous rib.

5. A door having a hinge side, along said

side a plurality of oppositely offset ribs, and along the parallel sides of said door extending from said hinge side outwardly straight ribs, said offset ribs and straight ribs merging to approximate parallel continuous ribs.

6. A door jamb, and double doors therefor, said jamb having hinges along opposite sides thereof for the doors, said sides connecting said hinge sides of the jamb having outwardly open grooves, and said doors having ribs running out as registering with said grooves, the first of said doors having along its free edge grooves extending beyond the ends of its ribs as running out with the roots thereof in the planes of the outer faces of the ribs, the second door having its adjacent free ends provided with ribs for entering the grooves of the first door, said ribs extending short of the ribs of the second door.

7. A door jamb having an endless groove differently directed on adjacent sides of said door, and a discontinuous rib adjacent said groove, and door means closable against the jamb for continuous sealed joint coaction with said groove.

8. A jamb, a door for the jamb having an outer side, a hinge on the door for the jamb having its pivot axis adjacent said outer side, said door along said hinge side having a pair of parallel ribs, one nearer the hinge axis deflected outward toward the plane of the door outer side, and the rib as more remote from the hinge axis being deflected inward away from the plane of the outer side of the door.

9. A door jamb having a pair of parallel grooves spaced from the front, the groove nearer the front being under-cut one way, and the groove more remote from the front being under-cut the opposite way, and a door provided with ribs for coacting with said grooves of the jamb.

10. A door jamb having a hinge pivot side, said door jamb also having a pair of grooves from said hinge pivot side thereof, and a door mounted on the hinge pivot, one of said grooves being on one side and the other on the other side of a plane at right angles to the plane of the closed door and through the axis of the hinge pivot.

11. A door having a hinge pivot, said door having a pair of ribs from said hinge pivot side thereof, one of said ribs being on one side and the other on the other side of the plane through the axis of the hinge pivot perpendicular to the plane of the closed door, and a jamb upon which the hinge pivot is mounted.

12. A jamb, a door therefor having a front side, and a hinge connection therebetween having a fixed pivot axis overhanging said front side of the door and spaced along the door front from the jamb, said door as to a plane perpendicular to the plane of the closed door front and through said hinge axis having a groove on the side of said plane

away from the jamb toward said door as closed.

13. A jamb, a door therefor having a front side, and a hinge connection therebetween having its pivot axis overhanging the door front side and spaced along the door front side from the jamb, and, as to a plane perpendicular to the plane of said closed door and through said pivot axis, there being rib and groove coaction between said door and jamb simultaneously on opposite sides of said perpendicular plane.

14. A jamb, a door therefor, and a hinge connection therebetween having its pivot axis overhanging over the door from the jamb, said jamb having a groove on one side of the said axis, and another groove on the other side of a plane through said axis perpendicular to the plane of the closed door, and said door having a pair of ribs one coacting with each groove.

15. A door jamb providing an opening, and double doors therefor, said jamb having inwardly overhanging hinges into the regions in front of said opening along opposite sides thereof for the doors, said jamb sides connecting said hinge sides of the jamb having outwardly open grooves, and said doors having ribs registering with said grooves, the first door to be closed having in the planes of the roots of said ribs grooves from the termini of said ribs, and the second door to be closed having ribs to interfit with said grooves of the first door.

16. A safe having a frame, a jamb carried in said frame to provide a door seat, said jamb inwardly extending from said frame to provide a door opening spaced in the plane of the frame from the frame, a door movable into said door seat and there having peripheral clearance as to the frame, and hinge mounting means for the door extending to said frame.

17. A safe having a corner frame, there being a door opening for said safe bounded by said corner frame, a jamb carried in said frame and providing a door seat, said jamb extending from said frame in the plane of the frame as a spacer for said door opening from the frame, and a door movable into said door seat to have in closed position a clearway peripherally as to the frame as determined by the spacer portion of said jamb.

In witness whereof I affix my signature.

CHARLES F. MEILINK.
